CLAIM

The ornamental design for a shoe sole, as shown and described.

DESCRIPTION

FIG. 1 is a front view of a shoe sole, showing my new design;

FIG. 2 is a back view thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof.

The broken lines depict environmental structure in the form of a shoe upper and outsole. The broken lines and structure they depict form no part of the claimed design.

1 Claim, 5 Drawing Sheets(56)
